UNITED STATES PATENT OFFICE.

PETER NIKOLAUS FELIX LANGEN, OF VALPARAISO, CHILE.

STEAM BOILER.

Application filed December 17, 1924, Serial No. 756,587, and in Germany February 28, 1924.

My invention relates to improvements in steam boilers, and more particularly in boilers in which in case of a sudden increase of the consumption of steam the feed water supply is interrupted, so that the increased amount of steam is supplied without changing the combustion of the fuel merely by vaporization of the water from high level to low level. The object of the improvements 5 is to provide a boiler in which the heat storing capacity of the boiler is increased by increasing the volume of water at the disposal for vaporization and included between the high and low levels. For this purpose the 10 number or the size of the upper steam and water chambers might be increased. This, however, is expensive particularly in high pressure boilers, and in addition only a part of the capacity of the steam and water 15 chamber is made use of for increasing the volume included between the high and low levels. My invention consists in increasing the said volume or the water storing effect by connecting the steam and water chamber or upper boiler drum with a subsidiary 20 chamber or chambers the height of which is substantially equal to the difference of the high and low levels, and which are disposed so that they are nearly or entirely filled 25 when the water within the upper boiler drum is at high level, and that they are nearly or entirely empty when the water within the 30 said boiler drum is at low level. Preferably the said subsidiary water chamber is made in sections each consisting of a pipe 35 equal or substantially equal in diameter to the distance between the high and low levels, in which case the said subsidiary chamber may be constructed from seamless tubes. 40 For the purpose of explaining the invention an example embodying the same has been shown in the accompanying drawing in which the same reference characters have 45 been used in all the views to indicate corresponding parts. In said drawing, Fig. 1, is a sectional elevation showing the boiler, and Fig. 2, is a top plan view with the top 50 part of the brickwork removed to show the pipes storing the water.

In the example shown in the drawing the boiler comprises a lower water drum *a* and an upper steam and water drum *b* connected by a bank of water tubes *c*. The letters *s* and *t* indicate respectively the feed water inlet and the steam off-take. Below

the tubes *c* there is a grate *d*, and in the flue there is a superheater made in two sections *e* and *f*, and an apparatus *g* for heating air for supporting combustion. The 60 portion of the brickwork in which the upper steam and water drum *b* is mounted is closed as against the flues by a partition *h*. Between the top wall *i* of the flues and a top wall *k* a horizontal chamber *l* is provided which contains a series of horizontal seamless pipes *m*. As shown the diameter of the said pipes is substantially equal to the difference of the high level *x* and the 65 low level *y*, and the top and bottom parts 70 of the pipes are located substantially at the same height as the said levels. The pipes are connected respectively with the water and steam spaces of the drum *b* by pipes *n* and *o*, the pipes *o* ending at the top parts 75 of the pipes *m* and the drum *b*, and the pipes *n* connecting the bottom parts of the pipes and the drum. Therefore, the volume 80 of water included between the high and low levels is large, and the boiler has a high heat storing effect. The aggregate capacity 85 of the pipes *m* is a multiple of the part of the capacity of the drum *b* included between the high and low levels *x* and *y*, so 90 that in case of a sudden increase of the consumption of steam the supply of the feed water may be interrupted and vaporization take place exclusively by the heat stored within the boiler and the pipes *m* for a substantial period of time, that is during 95 the time of the increased consumption of steam.

To insure a good heat and water storing effect care must be taken that the water within the pipes *m* be always at boiling temperature, and for this purpose I connect the pipes *m* by down-comers *p* with the lower water drum *a*, through which circulation of the water is maintained.

As appears from Fig. 2 the whole area of the boiler may be made use of for providing storing pipes *m*.

In view of the small diameter of the pipes *m* I am enabled to provide seamless pipes, 105 so that the cost of the system is comparatively low.

While in describing the invention reference has been made to a particular example embodying the same, I wish it to be understood that I do not limit myself to the construction and arrangement of the storing chamber *m* shown in the drawing, nor to 110

the use of the said storing chamber in a boiler of the type shown in the figures.

I claim:

1. A steam boiler, comprising a member having a steam space and a water space, and water storing means having a height substantially equal to the distance between the high and low levels of said member and disposed substantially between the horizontal planes passing through the high and low levels of said member and communicating near its bottom with the water space of said member, said storing means having a capacity sufficient to permit vaporization within the boiler in case of increased consumption of steam without supplying feed water to the boiler for a substantial period of time.

2. A steam boiler, comprising a member having a steam space and a water space, and water storing means having a height substantially equal to the distance between the high and low levels of said member and disposed substantially between the horizontal planes passing through the high and low levels of said member and communicating near its bottom with the water space of said member, said storing means having a capacity a multiple of the capacity of the part of said member included between the high and low levels of said member.

3. A steam boiler, comprising a member having a steam space and a water space, water storing means having a height substantially equal to the distance between the high and low levels of said member and disposed substantially between the high and low levels of said member, and separate pipes connecting said water storing means near its top and bottom respectively with the steam and water spaces of said member, said storing means having a capacity sufficient to permit vaporization within the boiler without supplying feed water thereto for a substantial period of time.

4. A steam boiler, comprising a member having a steam space and a water space, and substantially horizontal storage pipes having a diameter substantially equal to the distance between the high and low levels of said member and disposed substantially between the horizontal planes including the high and low levels of said member and communicating near their bottoms with the water space of said member, said pipes having a total capacity sufficient to permit vaporization of the water within the boiler without supplying feed water thereto for a substantial period of time.

5. A steam boiler, comprising a member having a steam space and a water space, substantially horizontal storage pipes having a diameter substantially equal to the distance between the high and low levels of said member and disposed substantially between the horizontal planes including the high and

low levels of said member, and separate pipes connecting said storage pipes near their tops and bottoms respectively with the steam and water spaces of said member, said pipes having a total capacity sufficient to permit vaporization of the water within the boiler without supplying feed water thereto for a substantial period of time.

6. A steam boiler, comprising an upper drum having a steam space and a water space, a lower drum communicating with the upper drum, water storing means having a height substantially equal to the distance between the high and low levels of said upper drum and disposed substantially between the planes including the said high and low levels and communicating near its bottom with the water space of said upper drum, said storing means having a capacity sufficient to permit vaporization in case of an increased consumption of steam for a substantial period of time without supplying feed water to the boiler, and a connection between said lower drum and said water storing means at a part away from said upper drum.

7. A steam boiler, comprising an upper drum having a steam space and a water space, a lower drum communicating with the upper drum, water storing means having a height substantially equal to the distance between the high and low levels of said upper drum and disposed substantially between the planes including the said high and low levels, separate pipes connecting said water storing means near its top and bottom respectively with the steam and water spaces of said upper drum, said storing means having a capacity sufficient to permit vaporization in case of an increased consumption of steam for a substantial period of time without supplying feed water to the boiler, and a connection between said lower drum and said water storing means at a part away from said upper drum.

8. A steam boiler, comprising an upper drum having a steam space and a water space, a lower drum communicating with the upper drum, substantially horizontal storage pipes having a diameter substantially equal to the distance between the high and low levels of said upper drum and disposed between the planes including the said high and low levels, separate pipes for each storage pipe connecting the same near their tops and bottoms respectively with the steam and water spaces of said drums, and down-comers connecting said lower drum with said storage pipes at parts away from said upper drum, the total capacity of said storage pipes being a multiple of that of the space of said upper drum included between the high and low levels of said upper drum.

9. A steam boiler, comprising a member

having a steam space and a water space, water storing means having a height substantially equal to the distance between the high and low levels of said member and disposed substantially between the horizontal planes passing through the high and low levels of said member and communicating near its bottom with the water space of said member, said storing means having a capacity sufficient to permit vaporization within the boiler in case of increased consumption of steam without supplying feed water to the boiler for a substantial period of time, heating means, and means for preventing direct action of said heating means on said water storing means.

10. A steam boiler, comprising a member having a steam space and a water space, substantially horizontal storage pipes having a 20 diameter substantially equal to the distance between the high and low levels of said member and disposed substantially between the horizontal planes including the high and low levels of said member and communicating near their bottoms with the water space of said member, said pipes having a total capacity sufficient to permit vaporiza-

tion of the water within the boiler without supplying feed water thereto for a substantial period of time, heating means, and 30 means for preventing direct action of said heating means on said storage pipes.

11. A steam boiler, comprising an upper drum having a steam space and a water space, a lower drum communicating with the 35 upper drum, water storing means having a height substantially equal to the distance between the high and low levels of said upper drum and disposed substantially between the planes including the said high 40 and low levels and communicating near its bottom with the water space of said upper drum, said storing means having a capacity sufficient to permit vaporization in case of an increased consumption of steam for a substantial period of time without supplying feed water to the boiler, heating means, and a connection between said lower drum and said water storing means at a part of reduced action of said heating means and 45 remote from said upper drum.

In testimony whereof I hereunto affix my signature.

PETER NIKOLAUS FELIX LANGEN.
